NOZZLE ADJUSTING CONSTRUCTION

Eugene F. Martinet, Cleveland, Ohio, assignor to
 The P. A. Geier Company, Cleveland, Ohio, a
 corporation of Ohio

Application June 2, 1937, Serial No. 145,998

13 Claims. (Cl. 15—16)

The invention relates to portable suction cleaners, including a nozzle and associated means which are adjustable to vary the relative location of the nozzle mouth with respect to the particular surface being cleaned; and more particularly, to means for effecting a proper nozzle adjustment for any particular surface and for locking the adjusting means in such position, controlled by the characteristics of the surface to be cleaned.

10 In a suction cleaner, whether or not a power driven rotary brush or agitator is provided in its nozzle mouth, substantially no cleaning takes place unless the nozzle mouth is properly located with respect to the particular surface to be cleaned, so as to provide the proper nozzle adjustment between the surface being cleaned and the nozzle mouth, as the cleaner is moved across the surface being cleaned.

Rugs having different nap thicknesses, and 20 floor surfaces of wood, linoleum, tile or the like, each require a different adjustment of the nozzle mouth with respect to the surface, to provide the proper nozzle adjustment for most effective cleaning.

25 Moreover, if the nozzle adjustment is too close to the surface being cleaned, the nozzle will tend to dig into the surface, and it will be difficult or hard to push the cleaner back and forth across the surface; or in the case of a bare floor and 30 the like, the cleaner nozzle may scrape the surface.

Thus, it is particularly important that the adjustment of the cleaner nozzle mouth with respect to the surface being cleaned, shall not be 35 any closer than is necessary to provide for the maximum amount of cleaning effect, with the least amount of effort on the part of the operator, and with a minimum of wear on the surface being cleaned.

40 Suction cleaners have heretofore usually been provided with manually adjustable means for varying the location of the nozzle mouth with respect to the surface being cleaned; but the only way the user of such a cleaner has of determining whether or not a proper nozzle adjustment 45 has been effected between the nozzle mouth and surface to be cleaned is by changes in the sound of the motor, or by changes in the sound of a revolving element in the nozzle, or by the lifting 50 of a portion of a carpet to the nozzle lips.

However, it is difficult to detect such changes in the sound of the motor or of a revolving element, or to observe the slight lift of a carpet; and such methods of determining when a proper 55 nozzle mouth adjustment has been made, are not

dependable, or at least are not understood by the average user of a suction cleaner.

I have heretofore provided signaling means for indicating when the proper nozzle adjustment has been effected in connection with the operation of manual adjusting means, as set forth in my copending applications, Serial No. 73,868, matured in Patent No. 2,120,011 and Serial No. 78,624, and such constructions are admirably satisfactory for the purposes intended, yet they depend upon the 10 operator coordinating the nozzle adjusting means and the signal means.

It has also been proposed to signal or control the nozzle adjustment by the amount of sink of the wheels, upon which the cleaner is mounted, 15 into the surface being cleaned; or by always adjusting the nozzle a definite fixed distance above the surface to be cleaned. However, all of these latter constructions do not permit or enable a cleaner equipped with the same to be used for 20 cleaning bare floor surfaces, tile, linoleum or the like.

The objects of the present invention include in general the provision of suction cleaning apparatus having a nozzle, which is self-adjusting 25 and which automatically locates itself at the proper position for satisfactorily cleaning a surface, whether the surface be a bare floor surface, or a floor surface covered with one of many kinds of covering material, by a simple manipulation by the user of the cleaning apparatus.

Further objects of the present invention include the provision of a suction cleaning apparatus having a suction passage or duct, and 35 nozzle adjusting means which are automatically locked in an adjusted position the instant that proper adjustment has been obtained.

Broader objects of the present invention include the provision of an improved suction cleaner in which the variation in the suction or 40 pressure of the air existing in a duct or chamber in the cleaner is utilized to lock the cleaner adjusting means the instant when a particular condition of the suction air has been obtained, such as when the suction or pressure in the 45 cleaner passages is such as will provide a maximum amount of cleaning, regardless of the character of the surface being cleaned.

Further objects of the present invention include the provision of suction cleaning apparatus 50 having adjusting means, locking means for the adjusting means actuated by changes in the pressure or suction existing in a duct for the cleaner, and release means for the locking means.

Further objects of the present invention include 55

the provision of automatic adjusting and locking means for the nozzle of a suction cleaner which may be readily and inexpensively applied to existing types and kinds of cleaners without difficulty, 5 and which are strong and rugged in construction and operation.

Moreover, it is an object of the present invention to provide an automatic nozzle adjusting construction for a suction cleaner which is controlled by the character of the particular surface 10 to be cleaned.

Another object of the present invention includes the provision of a portable suction cleaner having adjustable supporting means arranged to automatically adjust the nozzle with respect to a surface to be cleaned the instant that operation 15 of the adjusting means is initiated, and to hold the nozzle in such adjusted position until operation of the adjusting means is again 20 initiated.

The foregoing and other objects are attained by the suction cleaner, apparatus, parts, improvements, methods, combinations, and sub-combinations, which comprise the present invention; the nature of the same being set forth 25 in the following general statements and preferred embodiments of which, together with their mode of use are set forth in the following description; and which are particularly and 30 distinctly pointed out and set forth in the appended claims forming part hereof.

The nature of the improvements of the present invention may be described in general terms as including preferably in a portable suction 35 cleaner, a suction nozzle communicating with ducts or passages, means for flowing suction cleaning air into the nozzle and through the ducts, preferably wheel supporting means movably and preferably pivotally associated with 40 the nozzle, means for adjusting the wheel supporting means, means preferably actuated by changes in pressure in one of the ducts for locking 45 the adjusting means in an adjusted position the instant that proper adjustment of the nozzle mouth with respect to the surface to be cleaned has been effected, and release means for the locking means operable to initiate operation of the adjusting means.

By way of example, several embodiments of 50 the present improvements are illustrated in the accompanying drawings forming part hereof in which:

Figure 1 is a fragmentary side elevation of an 55 electrically operated, portable suction cleaner provided with one form of the improved nozzle adjusting and locking means;

Fig. 2 is an enlarged view similar to Fig. 1, with portions broken away and in section, illustrating 60 in full lines the position of the nozzle mouth and the parts of the adjusting and locking means just as the cleaner has been manipulated to initiate operation of the adjusting means; and showing in dot-dash lines the relative positions of certain of the same parts adjusted for the previous cleaning operation just 65 before the locking means has been released.

Fig. 3 is a bottom plan view of certain of the parts shown in Fig. 2;

Fig. 4 is a view similar to Fig. 2, showing the 70 location and relative positions of the cleaner nozzle mouth and adjusting and locking means after the adjusting means has operated to locate the nozzle mouth at the proper position to obtain maximum cleaning suction for the particular nap rug illustrated in Figs. 2 and 4 and 75

after the adjusting means has been locked in said adjusted position,

Fig. 5 is a bottom plan view of certain of the parts shown in Fig. 4;

Fig. 6 is a view similar to Fig. 4, but showing 5 the nozzle automatically adjusted to and locked in the proper position for obtaining maximum cleaning suction when cleaning a bare floor or the like;

Fig. 7 is an enlarged fragmentary sectional 10 view illustrating the means actuated by changes in the pressure or suction in the nozzle for locking the adjusting means; and

Fig. 8 is a fragmentary view similar to a portion of Fig. 6 illustrating a slightly modified 15 form of locking means.

Similar numerals refer to similar parts throughout the several figures of the drawings.

An electrically operated portable suction cleaner with a power driven rotary brush in 20 the nozzle chamber thereof and with a headlight, and provided with one embodiment of the present improvements, is shown in Figs. 1 to 7, inclusive, and is indicated generally at 10.

The suction cleaner 10 includes a motor 11 25 in a motor housing 12, associated with a fan housing 13 having a fan 14 therein secured on the motor shaft 14a, and a suction nozzle 15 is located adjacent to and communicates with the fan housing. An operating handle 16, and a dust bag 17 connected with the exhaust opening of the fan housing 13 are also provided for the cleaner; and the motor housing 12, the fan housing 13, and nozzle 15 are mounted on front casters 18 and preferably on adjustable double 30 rear caster means 19 for ambulant motion over a surface to be cleaned, the surface being a nap rug 20 in Figs. 2 and 4 and a bare floor 20a in Figs. 1 and 6. The cleaner 10 is also provided with headlight means indicated generally by 21. 40

The suction nozzle preferably includes walls forming a tubular neck 22 leading to the fan chamber 13, and a transversely elongated brush housing mouth 23 terminating in lip walls 23a and 23b.

A rotary brush indicated generally by 24, and provided with bristles 25 is preferably detachably and adjustably rotatably mounted in the suction mouth 23, and the brush 24 is preferably motor driven, as shown in the drawings, preferably by an endless flat band rubber belt 26, which passes over the brush pulley surface 27 and the pulley surface of motor shaft extension 28.

As shown, the lip walls 23a and 23b of the nozzle 55 15 are preferably provided at the entrance to the nozzle mouth 23 with a nozzle lip plate and brush guard 29.

The headlight means indicated generally by 21, as shown, include an upper centrally located 60 forwardly opening headlight shield 30 within the chamber 31 of which is operatively mounted an electric headlight bulb 32, which is associated with a source of power for the motor, the headlight 32 being preferably lighted when the motor and fan are in operation.

The front wheel or caster supporting means indicated generally at 18 preferably include front axles 33 extending respectively coaxially and laterally outwardly from boss portions 34 on 70 opposite sides of the lower portions of the fan housing 13. The front axles 33 have journaled thereon respectively, the front wheels or casters 18.

The adjustable double rear caster means gen- 75

erally indicated at 19, preferably include a bracket member generally indicated at 35, a frame member generally indicated at 36, a coil tensioned spring generally indicated at 37 and wheels or casters 38.

The bracket member 35 preferably includes an attaching plate portion 39 secured by any suitable means as by screws 40, to the underside of the rear end of the motor housing 12 within the downwardly opening shield 41. The plate portion 39 preferably has downturned ears 42 extending from its laterally opposite edge portions, and a hook shaped portion 43 terminating in a T-shaped cross piece 44 best shown in Figs. 4 and 5.

The frame member 36 preferably includes side bars 45 and 46 and a cross plate 47 slotted at 48. The slot 48 extends around a portion of the hook member 43 and above the T bar 44 thereof as well shown in Figs. 2, 4 and 6; and the rear ends of the side bars 45 and 46 carry axles 49 upon which the rear wheels or casters 38 are journaled.

The front end of side bar 45 and a middle portion of side bar 46 are journaled on axle 50, which extends through the ears 42 of the bracket member 35. The coil spring 37 is preferably mounted around the axle pin 50 and one end 51 thereof abuts against the mounting member 35, while the other end 52 thereof reacts against pin 53 carried by the side bar 45. The spring 37 normally urges frame member 36 to rotate in a clockwise direction about axle 50, or urges the motor housing 12, fan chamber 13 and nozzle 15 to rotate in a counter-clockwise direction around axle 50.

The side bar 46 extends forwardly from the axle 50 adjacent to and underneath the motor housing 12 and terminates in a rack portion generally indicated at 54. The rack portion 54 is provided with a series of teeth 55 formed on an arc about the axle 50 as a center, and the teeth 55 are preferably pointed with radial upper surfaces and tapered lower surfaces as shown. The upper end of the rack portion 54 terminates in an enlarged triangular shaped stop tooth 56 projecting forwardly beyond the pointed ends of the rack teeth 55 for a purpose to be later described.

An elongated preferably rectangular bottom plate 57 is mounted on the underside of the fan casing 13 and the plate 57 carries a generally S-shaped lever 58 pivoted thereon as at 59. One end of the lever 58 on one side of the pivot 59 is turned upward at 60 and terminates in a rearwardly projecting catch 61 having a flat undersurface and a curved or angled upper surface for selective engagement with any of the teeth 55 and 56, as will be presently described.

The other end of the lever 58 on the other side of the pivot 59 is turned upwardly at 62 and terminates in a boss 63 having an aperture 63a therein adjacent to one end of the rear nozzle lip wall 23b.

Movement of the lever 58 is controlled by the toggle mechanism best shown in Figs. 3 and 5, which includes the member 64 pivoted on plate 57, the member 65 pivoted on lever 58, the pin 66 extending between members 64 and 65 and compression spring 67 mounted on pin 66 and reacting between members 64 and 65. The toggle mechanism snaps the lever 58 either into the position of Fig. 3 or the position of Fig. 5 when moved from one position past center toward the other and holds the lever in such position when so actuated.

A bellows compartment is formed on the rear of nozzle lip wall 23b adjacent to lever boss 63, by a housing member 68 which may be secured by any suitable means as indicated at 69 to nozzle lip wall 23b. Referring particularly to Fig. 7, a series of apertures 70 are formed in the nozzle lip wall 23b for establishing communication between the nozzle chamber and the interior of the bellows housing. A preferably substantially cylindrical rubber bellows tube 71 is secured within the bellows housing 68 by a forward disk plate 72, which may be riveted at 73 to the nozzle lip wall 23b and clamps the forward peripheral edge 71a of the bellows tube 71 against the rear nozzle lip wall 23b. A similar disk plate 74 may be cemented or otherwise secured to the rear peripheral edge 71b of tubular bellows member 71 so that the plate member 74 acts together with the bellows member 71 as a diaphragm.

A series of apertures 75 are provided in the disk plate 72 for establishing communication through apertures 70 between the nozzle chamber and the interior of the bellows member 71. A pin or stud 76 is secured by any suitable means, as indicated at 77, to the bellows disk member 74 and extends rearwardly through aperture 78 in housing 68 and through aperture 63a in lever boss 63. One or more washers 79 may be provided on the pin 76 for abutment against the rear surface of lever boss 63 through the medium of 30 cotter pin 80 secured on pin 76.

Handle member 16, in accordance with usual suction cleaner construction, is arranged to swing freely in an arc extending counter-clockwise from the relative position of the handle 16 shown in Fig. 2; and stop lever 81 is arranged to abut a stop (not shown) on handle controlling plate 83, so that further rearward movement of the handle 16 reacts against motor housing 12 to initially rotate motor housing 12, fan housing 13 and nozzle 15 clockwise about front axles 33 until rear caster means axle 50 is moved downward to the position shown in full lines in Fig. 2. Further rearward and downward movement of handle 16 causes the entire cleaner to be lifted upwardly from the floor pivoting about the rear caster axles 49 in a clockwise direction, viewing Figs. 2, 4 and 6.

The operation of the improved suction cleaner 50 may be described as follows:

The manufacturer of a cleaner, such as the cleaner 10, determines and establishes, in designing the same, that degree of suction or sub-atmospheric pressure, or in other words, the drop from atmospheric pressure of the air existing in the cleaner nozzle 15 or other passages on the low pressure side of the fan, which is coincident with the correct adjustment of the entrance mouth of the nozzle with respect to the surface to be cleaned, whether it be a nap rug 20 or the like, or a bare floor 20a or the like; by which adjustment a maximum or predetermined cleaning action will occur in using the particular design of cleaner with its nozzle mouth correctly adjusted.

The manufacturer, having determined that degree of suction coincident with the proper adjustment of the nozzle entrance mouth to effect a maximum predetermined cleaning action, then 70 so designs the bellows 71 and diaphragm plate 74 thereof that the bellows will collapse from the position of Fig. 7, to that of Fig. 4 the instant that a suction or pressure has been obtained in the cleaner nozzle, which is coincident with 75

proper adjustment of the nozzle entrance mouth with respect to the surface being cleaned.

Referring now to Fig. 2, assuming that the cleaner has been operated on a surface with its parts in the relative positions shown in dot-dash lines, which is not a correct adjustment for the particular nap rug 20 shown, and assuming that the cleaner is to be operated on nap rug 20 with proper nozzle adjustment; the sequence of attaining the proper adjustment is as follows:

The motor 11 is running, causing fan 14 to induce an air flow into nozzle 15. The user pushes rearwardly downwardly on handle 16 to depress pivot pin 50 from the position shown in dot-dash lines to the position shown in full lines. In so moving the cleaner parts, the rack portion 54 moves from the dot-dash position to the full line position. This movement of rack portion 54 causes the particular teeth 55 engaged in dot-dash position with catch 61, by reason of the engaged tapered surfaces, to produce a cam action on the catch 61, which disengages catch 61 from teeth 55.

As the rack portion 54 moves to the limit of its downward movement, as shown in full lines, the tapered undersurface of stop tooth 56 engages catch 61 as shown, to move catch 61 to the full line position shown in Fig. 2.

Thus, viewing Fig. 3, lever 58 has been moved in a clockwise direction around pivot 59 and is held in that position by the toggle mechanism 64-67 so that the rack portion 54 is free to swing up and down within the limits of movement of frame member 36 about pivot point 50 without engaging catch 61 with any of the teeth 55.

The user or operator then releases downward pressure on the handle and spring 37 reacts between bracket member 35 and frame member 36 to raise the rear end of the cleaner and lower the nozzle from the position shown in full lines in Fig. 2 to the position shown in Fig. 4. At the instant that the nozzle lips attain the correct relation with respect to nap rug 20, as shown in Fig. 4, so that the cleaning air has attained a degree of cleaning suction to perform a maximum predetermined amount of cleaning, bellows 71-74 moves from the position shown in Fig. 7 to the position shown in Fig. 4.

When the bellows so moves, cotter pin 80 and washers 79 on member 76 engage boss 63 on lever 58 and pivots lever 59 in a counter-clockwise direction, viewing Fig. 5, from the position shown in Fig. 3 to the position shown in Fig. 5. When lever 58 so moves, catch 61 engages teeth 55 on rack portion 54, as shown in Fig. 4, to lock the adjustable double rear caster means in the position shown in Fig. 4, whereupon the cleaner may be operated to clean nap rug 20 with the nozzle adjusted to perform a maximum amount of cleaning for said nap rug 20.

If during the cleaning operation, the handle 16 is depressed rearwardly downwardly to lift the cleaner from the floor, adjustment of the nozzle will of course be again initiated, but the nozzle will always return to and become locked in the adjusted position shown in Fig. 4 so long as it is being operated on nap rug 20.

Referring to Fig. 6, the parts are shown in full lines when the cleaner is adjusted and locked in adjusted position for cleaning a bare floor or the like. A large number of teeth 55 are provided to enable the cleaner to be adjusted automatically and locked in any one of a plurality of adjusted positions within the limits of movement of rack portion 54.

Referring to Fig. 8, wherein a modified form of rack portion 64a is shown, the teeth 55a are square teeth rather than tapered teeth and the catch 61 is square rather than tapered. This type of construction requires a manual release of catch 61a from teeth 55a every time the cleaner is to be adjusted, rather than obtaining release of the locking means by the downward movement of the handle.

The purpose of the modified form of construction shown in Fig. 8 is to avoid the necessity of going through an adjusting operation whenever the cleaner is tilted on its back wheels to go over the edge of a carpet to clean a fringe, or tilted for any other purpose.

The present improvements as above described by way of example, thus provide a suction cleaner in which the variation in the suction or pressure of the air existing in the cleaner passages is utilized to control the adjustment of the cleaner nozzle, which adjustment automatically operates to move the nozzle to a correct position to perform a maximum predetermined amount of cleaning on any particular surface immediately after operation of the adjusting means has been initiated.

Moreover, the present improvements attain proper adjustment and locking of the cleaner parts in adjusted position by a very simple manipulation by the user. In the particular embodiment shown, the manipulation is of the cleaner handle to a rearwardly depressed position and then a release of downward pressure on the handle to initiate operation of the automatic adjustment.

Accordingly, the present improvements provide in a simple but rugged manner, means for attaining the objects heretofore set forth by providing for the automatic adjustment of the nozzle mouth and automatic locking of the same in any adjusted position with respect to any one of different surfaces or covering materials upon which the cleaner is operated, so that a maximum predetermined cleaning effect is produced and yet the cleaner is always easy to push and cannot mark or scratch a bare surface being cleaned.

Having now described the features of the invention, the construction and operation of preferred forms of the invention, and the advantages and results obtained thereby; the new and useful parts, elements, devices, combinations and constructions, and reasonable mechanical equivalents thereof, obvious to those skilled in the art, are set forth in the appended claims.

I claim:

1. In a suction cleaner, a suction nozzle having an entrance mouth, a fan for producing suction in said nozzle, means for adjusting the position of the mouth with respect to the surface to be cleaned so that proper cleaning suction can be obtained in the nozzle, and means operated by the suction in the nozzle when proper cleaning suction has been obtained therein for locking the adjusting means in the adjusted position coincident with the attainment of said proper cleaning suction.

2. In a suction cleaner, a suction nozzle having an entrance mouth, a fan for producing suction at said mouth, a duct communicating with the fan and mouth in which the pressure attains a predetermined amount relative to atmospheric pressure when the mouth is so located with respect to the surface to be cleaned that proper cleaning suction is obtained at the mouth, means

for adjusting the location of the mouth to obtain said proper cleaning suction thereat, means operated by the pressure in the duct when proper cleaning suction has been obtained at the mouth for locking the adjusting means in the adjusted position coincident with the attainment of said proper cleaning suction.

3. In a suction cleaner, a nozzle, means for adjusting the nozzle with respect to the surface to be cleaned so that proper cleaning suction can be obtained in the nozzle including means for initiating the operation of the adjusting means, and means controlled by the suction in the nozzle for stopping operation of the adjusting means at a predetermined position coincident with the attainment of said proper cleaning suction.

4. In a suction cleaner, a nozzle, means for adjusting the nozzle with respect to the surface to be cleaned, and means operatively associated with said adjusting means and operated by the suction in the nozzle to lock the adjusting means the instant that a nozzle adjustment is obtained which provides a predetermined maximum cleaning action.

5. In a suction cleaner provided with a suction nozzle, a support for the cleaner, adjusting means for raising and lowering said nozzle relative to said support, and means including bellows controlled by the suction of the nozzle adapted to interlock with said adjusting means upon the attainment of a predetermined degree of suction in the nozzle.

6. In a suction cleaner having supporting wheels and a nozzle adjustable with respect to the surface being cleaned, means for adjusting the height of said nozzle in accordance with the character of the surface for obtaining a predetermined cleaning suction in said nozzle including means for manually initiating the operation of said adjusting means, and means actuated by the suction in the nozzle upon the attainment of said predetermined cleaning suction in said nozzle for locking the adjusting means.

7. In a suction cleaner, a nozzle, means for adjusting the nozzle with respect to the surface to be cleaned, locking means for the adjusting means actuated by changes in the pressure in the nozzle when a predetermined suction exists in the nozzle, and release means for the locking means.

8. In a suction cleaner, a nozzle, means for adjusting the nozzle with respect to the surface to be cleaned, means controlled by the suction in the nozzle for locking the adjusting means in an adjusted position, and manually controlled release means for the locking means operable to initiate operation of the adjusting means.

9. In a suction cleaner having a housing including a nozzle, an adjustable wheeled support for raising or lowering the housing, means operative through said wheeled support for raising the nozzle, said support including a member pivotally mounted on the housing, means interposed between said member and housing normally urging said nozzle downward toward a surface to

be cleaned, and lock means actuated by the suction in the nozzle for locking said member when a predetermined suction exists in the nozzle.

10. In a suction cleaner having a housing including a nozzle, an adjustable wheeled support for raising or lowering the housing, means operative through said wheeled support for raising the nozzle, said support including a member pivotally mounted on the housing provided with a rack bar, means interposed between said member and housing normally urging said nozzle downward toward a surface to be cleaned, and lock means actuated by the suction in the nozzle for locking said rack bar when a predetermined suction exists in the nozzle.

11. In a suction cleaner having a housing including a nozzle, an adjustable wheeled support for raising or lowering the housing, means operative through said wheeled support for raising the nozzle, said support including a member pivotally mounted on the housing provided with a rack having tapered teeth, means interposed between said member and housing normally urging said nozzle downward toward a surface to be cleaned, and lock means actuated by the suction in the nozzle for locking said member when a predetermined suction exists in the nozzle, said lock means including a catch having a tapered portion for engagement with said tapered teeth.

12. In a suction cleaner having a housing including a nozzle, an adjustable wheeled support for raising or lowering the housing, means operative through said wheeled support for raising the nozzle, said support including a member pivotally mounted on the housing, means interposed between said member and housing normally urging said nozzle downward toward a surface to be cleaned, and lock means including pressure operated means and a toggle controlled lever having a catch, said pressure operated means being actuated by and upon the attainment of a predetermined suction in the nozzle to engage said catch with said member for locking said member.

13. In a suction cleaner having a housing including a nozzle, an adjustable wheeled support for raising or lowering the housing, means operative through said wheeled support for raising the nozzle, said support including a member pivotally mounted on the housing provided with a rack bar having tapered teeth and a projecting stop tooth, means interposed between said member and housing normally urging said nozzle downward toward a surface to be cleaned, lock means including a pressure device and a toggle controlled lever operated to a position locking said toothed rack bar by the pressure device by and upon the attainment of a predetermined suction in the nozzle, said stop tooth engaging the toggle controlled lever at the limit of movement of said member in one direction to move the toggle controlled lever to its other position out of the path of travel of the rack bar teeth for subsequent operation by the pressure device.
